UNITED STATES PATENT OFFICE.

WILLIAM F. PAGEL, OF SYCAMORE, ILLINOIS.

METHOD OF AND MEANS FOR FEEDING CARBURETED AIR TO INTERNAL-COMBUSTION ENGINES.

Application filed July 15, 1918. Serial No. 244,938.

To all whom it may concern:

Be it known that I, WILLIAM F. PAGEL, a citizen of the United States, residing at Sycamore, in the county of De Kalb and State of Illinois, have invented a certain new and useful Improvement in Methods of and Means for Feeding Carbureted Air to Internal-combustion Engines, of which the following is a full, clear, concise, and exact description, reference being had to the accompanying drawings, forming a part of this specification.

My invention relates to improvements in method of and means for feeding liquid fuel to internal combustion engines, and has special reference to engines of the two-cycle type.

The object of my invention is to provide an improved method and means for the purpose specified, or, in other words, for pre-vaporizing liquid fuel for such engines.

A further object of my invention is to provide a carburetor of simple design, whereby I can best practice my method of feeding hydro-carbon oil fuel into the base of two-cycle internal combustion engines from a reservoir at a lower level; which shall insure the feeding of the fuel in a finely divided or pre-vaporized condition; which shall include the suction of the liquid from a reservoir at a lower level and its propulsion into an intermediate chamber where it is admixed with a relatively small quantity of air, and then its suction into the base of the engine and its mixture with a greater quantity of air.

My invention consists in a method of pre-vaporizing liquid fuel for internal combustion engines, which consists in projecting the liquid into a relatively small chamber wherein it is mixed with a relatively small quantity of air, in the form of mist or a vaporized condition, then drawing this mixture into the engine with an added quantity of air, whereby the small particles or atoms of liquid both in vaporized and liquid form produced in the small chamber are so widely separated that the possibility of reforming liquid drops of any substantial size is practically eliminated.

My invention also consists in a carburetor for application upon and to an internal combustion engine of the two-cycle type, by means of which the liquid fuel is lifted

from a lower reservoir upon the inward stroke of the piston and sprayed in the form of a fine mist into a relatively small chamber filled with air, and then upon the suction of the engine the rich mixture is drawn into the base of the engine together with a greater quantity of air.

My invention also consists in the herein described method of and means for producing and feeding carbureted air.

My invention will be more readily understood by reference to the accompanying drawing forming part of this specification and in which:

Figure 1 is a fragmentary side elevation of an engine of the two-cycle type, equipped with a carburetor which portrays the best form which I have yet devised of a carburetor suitable for practicing my invention;

Figure 2 is a top plan view of the carburetor;

Figure 3 is a vertical section of the carburetor, on the line 3—3 of Figure 1 with the air regulator removed;

Figure 4 is a horizontal sectional view on the line 4—4 of Figure 1; and

Figure 5 is a vertical sectional view substantially on the line 5—5 of Figure 2, the air regulator being in place.

The carburetor depicted in the drawings is typical of a suitable carburetor for carrying my improved method into effect, and the carburetor therein shown discloses my invention relatively to carburetors.

In said drawing 1 is a one cylinder two cycle engine, having a cylinder 2, a crank case 3, and a crank shaft 4. The engine is mounted upon a hollow base 5, in which I store the liquid fuel such as gasoline for use in the engine.

My carburetor 7, which I secure on the crank case 3, comprises a casing 8 provided with a vertically extending cylindrical chamber 9, closed at its lower end by an integral wall 10 and at its upper end by a screw threaded plug 11. I divide this chamber into an upper part 12 and a lower part 13 by means of a valve 14, which is held down upon its seat 15 by coiled spring 16 surrounding the valve stem 17. The upper end of the valve stem enters and is guided in a guide opening 18 in the plug 11.

The upper chamber 12 is in free and direct

communication with the interior of the crank case by means of the passage 19, and the opening 20 in the wall of the crank case with which the mouth of the passage 19 registers. Consequently the chamber 12 is always subject to the pressure in the crank case.

It will be understood that the piston of the engine on its outward stroke produces a partial vacuum in the crank case and on the other hand on its inward stroke produces more or less pressure therein. The valve 6 prevents any excess either of vacuum or pressure.

15 The lower chamber 13 is in direct and free communication with an air inlet passage 21 which is provided with means for regulating the quantity of air to be admitted to the chamber 13.

20 I connect the lower chamber 13 with the fuel supply through a small horizontal passage 22 controlled by a needle valve 23 which is adjustably mounted in a threaded opening 24 in the casing 8. The needle valve 23 is of peculiar construction, being rather bluntly conical in shape and its base 25 is threaded on its periphery to fit the threaded opening 24. The stem 26 of the valve is much smaller in diameter than the base of the head and I guide this stem and pack it against the escape of gas in a guide sleeve 27, screwed into the outer end of the opening 24 and provided, on its outer end, with a packing nut 28, between which and the end 35 of the sleeve 27, I provide packing 29. I substantially conform the forward end 30 of the opening 24 with the coned shape of the valve 23, so that when the valve 23 is adjusted nearly to the point of closing the

40 passage 22 there is provided a conical shell like space 31, surrounding the head of the valve. I connect this space 31, between its ends, with the fuel oil reservoir by means of a depending pipe 32, which I secure in the lower side of the casing 8 and which is long enough to reach nearly to the bottom of the base 5 of the engine. I connect the threaded opening 33, which receives the pipe 32 to the

45 space 31 by a small passage 34 which enters such space between the ends thereof. I provide the lower end of the pipe 32 with a check or foot valve 35 comprising a casing 36 screwed on to the lower end of the pipe and provided with a ball check valve 37. I 50 provide a small inlet passage 38 below the check valve and to prevent the entrance of extraneous matter I surround the casing 35 with a cylindrical wire screen 39, reducing the diameter of the casing beneath the screen 55 to provide the cylindrical suction space 40.

To lift the fuel oil through the pipe 32 I connect the chamber 24 with the upper chamber 12 by means of a small passage 41 between the ends of which I provide a small 60 ball check valve 42 which prevents the flow

of fluid from the valve chamber 24 to the chamber 12 and permits pressure in the chamber 12 to enter the valve chamber 24.

Upon the inward stroke of the piston of the engine, pressure is produced in the crank case which is communicated to the chamber 9 and tends to press the valve 14 upon its seat. The pressure also passes through the passage 41 beneath the check valve 42 into the valve chamber 24. I make use of this pressure to lift the fuel oil by providing a very small, central, needle-like passage 43 in the valve 23, which communicates with the chamber 24 through a lateral passage 44 in the stem 26 of the valve. The air or gas which is driven into the valve chamber 24, when the pressure is produced in the crank case, causes the needle valve 23 to act as an ejector or injector and produces a slight vacuum in the space 31 surrounding the valve 23, sufficient to raise the liquid fuel through the pipe 32 and the passage 34 and into the space 31, from which it is drawn and driven into the lower chamber 13 in the form of a light spray or mist.

The projection of the liquid fuel into the lower chamber 13 is momentarily only and does not endure long enough to project any fuel up through the inlet passage 21. Upon the return or outward stroke of the piston of the engine, a partial vacuum is created in the crank base which immediately exhausts the upper chamber 12 and the air pressure enters through the air inlet 21, overcomes the tension of the spring 17, lifting the valve 14, and the air is then drawn through the air inlet 21 and the lower chamber 13, carrying with it the charge of fuel just previously projected into the lower chamber 13.

For regulating the quantity of air admitted through the air inlet 21 and for the purpose of priming the engine when starting, I provide a cap 45 for the outer end of the air inlet passage 21. This cap 45 is internally screw threaded to screw upon the nozzle 46 through which the passage 21 extends and I provide air admission openings 47 in the side wall of the cap 45, communicating with the interior 48 of the cap. The amount of air admitted to the passage 21 is adjusted by screwing the cap 45 up and down. For priming the engine, or in other words producing a very rich fuel mixture, I admit very little free air. This is accomplished by screwing the cap 45 down nearly as far as it will go. For convenience in adjusting the cap 45 and for retaining it in its adjusted position I provide the valve rod 49 in the form of a heavy wire which I project through the wall at the outer end of the cap and the inner end of the rod projects down into the passage 21. I rigidly secure the rod 49 to the cap by solder or otherwise and I provide the rod with a

- handle 50 at its outer end. I hold the rod 49 from turning by means of a small spring wire 51 which I secure in the inner end of the rod 49. I project the ends 52 of the 5 spring wire 51 outwardly so that they contact with the wall of the passage 21 with sufficient friction to prevent the vibration of the engine, when running, turning the cap 45.
- 10 By means of my improved carburetor I am enabled to practice my improved method of feeding pre-vaporized liquid fuel to a two-cycle engine, which method consists in forcibly injecting the fuel oil by means of 15 gas into a chamber in the form of a light mist or vapor, where the fuel is mixed with a relatively small quantity of air, then drawing the mixture into the base of the engine and admixing the mixture with a larger 20 quantity of air, as it is thus drawn into the engine.
- As many modifications of my invention will readily suggest themselves to one skilled in the art I do not limit or confine 25 my invention to the specific steps or structures herein shown and described.
- I claim:
1. The herein described method of carbureting air and feeding it to an internal 30 combustion engine, which consists in forcibly projecting a gaseous mixture, into a relatively small space, through an ejector by the action of the engine piston, the ejector connected to a source of supply of liquid 35 fuel whereby a measured quantity of liquid fuel is drawn through the ejector and is broken up into a fine mist-like cloud and the relatively small space is filled with a rich mixture, then successively drawing free 40 air through said relatively small space into the crank case of the engine by the action of the engine piston whereby the rich mixture is diluted and mixed with the free air, then by the action of the engine piston 45 drawing the diluted mixture into the cylinder of the engine for combustion purposes.
  2. The herein described improvement comprising a two-cycle internal combustion engine crank case, in combination with a mixing 50 chamber having valve controlled communication therewith, pressure fuel injecting means in communication with the crank case, adapted to project liquid fuel into said chamber, the valve controlling communication between the chamber and the crank case being adapted to be opened by suction from the crank case, and said chamber having an air inlet.
  3. In a carburetor for use on a two-cycle 55 internal combustion engine and adapted to deliver fuel into the crank case thereof, said carburetor having a carbureting chamber divided into two parts by a spring controlled suction valve, the part beneath the 60 valve having a freely open air inlet the other part being adapted to be placed in free communication with the crank case, a small passage connecting the two parts whereby pressure can pass into the part beneath the valve from the crank case, means 65 associated with said passage for feeding fuel oil into the part beneath the valve through said passage, said valve being adapted to be lifted for opening communication between the part beneath the valve and the 70 crank case by suction from the crank case.
  4. In a carburetor for a two-cycle engine, a carburetor chamber divided into two parts by a suction valve, the part above the valve adapted for communication with the crank 75 case of an engine, the part below the valve provided with an open air inlet, a relatively small passage connecting the two parts around the valve, a fuel oil injector interposed in said passage adapted when pressure 80 is produced above said valve to eject liquid fuel in the form of a spray or mist thru said small passage into the space below the valve, said suction valve being adapted to be opened when a vacuum is produced in the 85 crank case and permit such fuel and air from said air inlet to enter the crank case.
  5. A two cycle internal combustion engine in combination with a carburetor including 90 an injector for delivering fuel to a carbureting chamber, comprising a coned head arranged in a similarly coned chamber and providing a conically shaped shell-like space, a central passage extending centrally through said head and registering with a similar passage leading from the coned 95 chamber and entering the carbureting chamber, means for forcing compressed air through said registering passages into said carbureting chamber at intervals, and a fuel 100 feed inlet entering said space between the ends thereof and leading to a lower level fuel supply for feeding liquid fuel into said compressed air as same flows into said chamber.
  6. In a carburetor, a carbureting chamber 105 adapted to have liquid fuel forced thereinto at intervals by means of compressed air, an upwardly extending air inlet passage leading into said chamber, a cap adapted to close the outer end of said air inlet passage and provided with adjustable air inlet openings 110 in combination with means for causing air to flow to the carburetor through said inlet passage alternately to the projection of fuel 115 into said chamber.
  7. The herein described improvement, comprising a two cycle internal combustion engine crank case, in combination with a mixing chamber having valve controlled communication therewith, pressure fuel injecting means in communication with the crank case, adapted to project liquid fuel 120 into said chamber, a valve controlling communication between the chamber and the 125

crank case being adapted to be opened by suction from the crank case, said mixing chamber having an air inlet inclined upwardly therefrom, and means for adjusting 5 said inlet to control or stop the flow of air therethrough.

8. A two cycle internal combustion engine having a closed crank case, in combination with air carbureting means comprising, a 10 mixing chamber in free communication with the crank case, a second mixing chamber in free communication with the atmosphere, a check valve opened by suction within the crank case controlling communication between said chambers, a by-pass of small bore connecting said chambers, a liquid fuel feed communicating with said by-pass, an injector associated with said by-pass for projecting liquid fuel from said fuel feed into said 15 second chamber upon the pressure stroke of the engine, and means preventing the drawing of liquid fuel through the by-pass into

the upper chamber upon the suction stroke of the engine.

9. The herein described method of carbureting air and feeding it to an internal combustion engine, which consists in intermittently projecting a stream of gaseous mixture from the crank case of an engine by the action of the engine piston, drawing 25 liquid fuel from a source of supply by said projected stream and forcing it into a relatively small substantially closed space thereby filling said space with fuel in finely atomized form and air in the form of a rich mixture, intermittently drawing free air through said space into a larger space by the action of the engine piston thereby diluting said rich mixture, and finally from said larger 30 space into the cylinder of the engine. 35

In witness whereof I hereunto subscribe my name this 14th day of June, A. D. 1918.

WILLIAM F. PAGEL.
